UNITED STATES PATENT OFFICE

HENRY R. MERSELES, OF BRONXVILLE, NEW YORK, ASSIGNOR, BY MESNE ASSIGNMENTS, TO HOBART MANUFACTURING COMPANY, OF TROY, OHIO, A CORPORATION OF OHIO

DISTRIBUTOR FOR WASHING MACHINES

Application filed May 20, 1924. Serial No. 714,568.

This invention relates to washing machines of the type in which a rotary distributor is used to distribute the washing medium over the articles to be washed. The invention 5 aims to improve the operation of such machines and to increase the life of such machines by providing an improved bearing arrangement for the rotary distributor.

10 While the invention may be incorporated in washing machines of many different sorts, it is particularly useful in machines for washing dishes and in machines for washing metal parts. It may be noted that the expression "washing" is herein used in a broad sense to 15 include treatment of the surface of articles with any liquid, including cases in which the liquid has a chemical effect on the articles as well as those which have a merely detergent effect.

20 I have found that the wear on the thrust
bearings of the rotary distributors used in
washing machines is in large part the result
of unbalanced liquid pressures within the dis-
tributors. The present invention affords a
25 simple and effective means for eliminating
such unbalanced pressures, and provides also
an improved mounting for such distributors.

The invention may be incorporated in various different mechanical structures and may 30 most clearly be understood from a detailed description of the structures embodying it which are shown in the accompanying drawings, in which:—

Fig. 1 is a sectional elevation of a dish washing machine having two rotary wash water distributors located respectively above and below the dish support;

Fig. 2 is an enlarged side elevation of one of the distributors shown in Fig. 1 and its 40 mounting, sectioned on the line 2—2 of Fig. 3;

Fig. 3 is a top view of the distributor and mounting shown in Fig. 2;

Fig. 4 is a fragmentary horizontal section taken on the line 4—4 of Fig. 2;
45 Fig. 5 is a top view of a four-arm distributor adapted for use in large dish washing and parts washing machines showing the

Fig. 6 is an enlarged fragmentary horizontal section of the distributor shown in Fig. 50

5, the section being taken on a plane corresponding to the section plane of Fig. 4.

The dishwashing machine shown in Fig. 1 comprises a casing 10 having in its bottom a tank 11, from which wash water is pumped into a stand pipe 12 having a lower branch 13, and an upper branch 13'. The lower branch 13 terminates in an elbow 14 having an upwardly directed outlet opening, while the upper branch 13' terminates in a similar downwardly directed elbow 14'. The dishes or other articles to be washed are placed on a support 15 between the elbows 14 and 14'. The wash water is distributed over the dishes by rotary distributors 20, 20', mounted at the discharge openings of the elbows 14 and 14'. 55 60 65 70

The distributor 20 shown in Figs. 1, 2, 3 and 4 includes a central hub 21 and two hollow arms 22 extending radially outward from the hub at diametrically opposite points. The arms may be made integral with the hub as shown. The arms 22 are provided with nozzles 23 containing discharge openings 24. The nozzles on the ends of the arms are turned at an angle to the axis of the hub in order to cause the distributor to rotate by the reaction of the liquid discharged through them. The end nozzles may be adjustably mounted as shown. 70 75

The distributor 20 is rotatably mounted at the outlet end of the elbow 14. The mounting of the distributor constitutes a feature of the invention. In the hub of the distributor is a spider 25, which may be made integral with the hub as shown. A sleeve 27 having an external flange 28 at its upper end is rigidly secured to the spider 25 by screws 29 so that it is in effect a part of the distributor. The sleeve 27 is rotatably mounted on a pin 30 which is fixed in the elbow 14 and projects axially through the outlet opening 31 of the elbow. Graphite bushings 32, 33 may be secured to the inner surface of the sleeve 27 at the upper and lower ends thereof in order to provide a good bearing against the outer surface of the pin 30. Thrust bearings are provided at each end of the sleeve 27. These may include a graphite disc 34 at the inner end of the sleeve and bearing against a washer 35 which bears against the inner surface of the 10

elbow 14 at the inner end of the pin 30; and a graphite washer 36 at the outer end of the sleeve which bears against a disc 37 fixed at the outer end of the pin 30 by means of a nut 38.

It will be noted that the mounting described provides a long bearing for the distributor, which prevents wobbling of the distributor in its rotation.

- 10 The distributor has an axial intake opening 40 in a collar 41 which surrounds the outer end of the elbow 14, so that the intake opening 40 communicates with the outlet opening 31 of the elbow. A clearance is allowed between the collar 41 and the elbow 14 so that there is no friction at this point to retard the rotation of the distributor. Because of the long bearing provided for the distributor on the pin 30 it is possible to avoid 15 frictional contact and at the same time to make this clearance very small so that no material portion of the liquid escapes between the elbow and the distributor. Escape of the liquid may be further impeded by an internal annular flange 43 in the opening 40, which lies just out of contact with the end of the elbow 14.

It will be noted that the distributor which has been described contains an intake opening 40 at one side of its plane of rotation and discharge openings 24 at the other side of its plane of rotation. In order that flow losses may be avoided and the pressure of the liquid at the discharge openings may be as nearly 20 as possible equal to that at which the liquid is supplied to the elbow 14, the internal cross-sectional area of the elbow and the intake opening of the distributor is made much larger than the combined area of the discharge openings. So far as pressures acting 25 in the direction of the axis of the distributor are concerned, the effective area of the opening 40 is the area included by the inner surface of the collar 41, since the inwardly projecting flange 43 receives fluid pressure on each side and may, therefore, be neglected; and the effective area of the discharge openings 24 is the sum of the areas of the projections of these openings on the plane of rotation 30 of the distributor. Since, for the reason mentioned, the effective area of the discharge openings is made materially less than that of the intake opening 40, the fluid pressure in a distributor similar to that described and 35 containing no openings other than the intake and discharge openings, is unbalanced and produces an excessive thrust on the outer thrust bearing of the distributor. It has been found that this thrust tends to retard the rotation of the distributor and causes very 40 rapid wear of the outer thrust bearing. An important object of the present invention is to eliminate this thrust. This is accomplished, in the distributors illustrated, by forming in the distributor an additional

opening 50 on the side of the distributor opposite to that in which the intake opening 40 is formed, and by providing the additional opening 50 with a closure 37 which is supported independently from the distributor so that the fluid pressure on the closure does not cause an outward thrust on the distributor. A clearance is allowed between the outer edge of the closure disc 37 and the inner surface of the opening 50 so that there is no friction at this point to impede the rotation of the distributor. The fit is, however, sufficiently close to prevent any material escape of fluid at this point, and furthermore such liquid as leaks out around the disc 37 is directed in the same direction as the liquid escaping through the discharge openings. Such liquid is, therefore, not wasted, but assists in the washing.

The area of the additional opening 50 is different from the area of the intake opening 40 and is most desirably made such that the total effective area of the opening or openings at one side of the distributor is equal to the total effective area of the opening or openings at the other side of the distributor. Where the discharge openings are on the opposite side of the distributor from the intake opening, as shown, this is accomplished by making the area of the opening 50 equal to the difference between the effective area of the intake opening 40 and the effective area of the discharge openings 24. This results in balancing the inward and outward fluid pressures within the distributor so that the fluid pressure causes no thrust on either of the thrust bearings. This condition holds true regardless of the amount of the fluid pressure which may be applied to the distributor.

The only thrust on the inner bearing 34 is that caused by the weight of the distributor, and there is no thrust on the outer thrust bearing 36, so that this bearing, if desired, may be altogether omitted. The upper distributor 20' (Fig. 1) is similar to the distributor 20, but by reason of its position the weight of this distributor is borne on its outer thrust bearing. For convenience in manufacture, therefore, it is desirable to provide two thrust bearings for each distributor so that any distributor may be used either on the lower elbow 14 or the upper elbow 14'.

It is apparent that the opening 50 might be given such an area that the fluid pressure within the distributor would exactly balance the weight of the distributor at any given pressure, and that in this way both thrust bearings might be relieved of all thrust. Such a modification of the device shown is desirable in the cases where the distributor is of considerable weight and where a constant fluid pressure is used. I have found, however, that in most washing machines the

fluid pressure cannot accurately be determined in advance and that the wear on one of the thrust bearings caused by the weight of a distributor amounts to very little. In the preferred embodiment of my invention, therefore, I make the area of the opening 50 such as to balance the fluid pressures within the distributor, so as to adapt to use with any desired fluid pressure.

10 Figs. 5 and 6 illustrate the application of the invention to a rotary distributor of a type used in large parts washing machines. The distributor 60 shown in these figures is in general similar to the distributor 20 15 which has been described, except that it is provided with four radial arms 62 instead of only two arms, and consequently with a greater number of discharge openings 64. It follows that in order to balance the fluid 20 pressures in this distributor there is more difference between the effective areas of its intake opening 65 and its additional opening 66 than there is between the corresponding openings in the two-arm distributor 20.

25 What I claim is:

1. In a dishwashing machine, the combination of a conduit having an outlet opening, a pin fixed in said conduit and extending axially through said outlet opening, a distributor 30 rotatably mounted on said pin and having discharge openings, an axial intake opening communicating with the outlet opening of the conduit, and a second axial opening opposite said intake opening and of 35 materially greater diameter than the pin, and a closure for said second axial opening fixed on the pin and having a running fit with the periphery of said second opening.

2. In a washing machine, the combination 40 of a conduit having an outlet opening, a pin fixed in said conduit and extending axially through said outlet opening, a distributor having radial arms containing discharge openings and a central hub having on one 45 side an inlet opening communicating with the outlet opening of the conduit and on its other side an additional opening, an open spider fixed in said hub and rotatably mounted on said pin, and a disc fixed on said pin 50 and closing the outer opening of the hub.

3. In a washing machine, the combination 55 of a conduit having an outlet opening, a pin fixed in said conduit and extending axially through said outlet opening, a distributor having radial arms containing discharge 60 openings, and a central hub having at its inner side an intake opening connecting with the outlet opening of the conduit, and at its outer side an additional opening, a spider fixed in the hub of the distributor, a sleeve secured to said spider extending into the conduit and rotatably mounted on the pin, and a disc fixed on the pin and serving to close the outer opening in the hub.

65 4. In a washing machine, the combination

of a conduit having an outlet opening, a pin fixed in said conduit and extending axially through said outlet opening, a distributor having radial arms containing discharge 70 openings and a central hub having at its inner side an intake opening communicating with the outlet opening of the conduit, and at its outer side an additional opening, a spider fixed in the hub of the distributor, a sleeve secured to said spider extending into the 75 conduit and rotatably mounted on the pin, and a disc fixed on the pin and serving to close the outer opening in the hub, a clearance being allowed between the conduit and the intake opening of the hub and between 80 the disc and the outer opening of the hub so that no friction occurs at these points.

5. In a washing machine, the combination 85 with a conduit terminating in an elbow having an open end and a rotary reaction driven distributor having an axial opening communicating with the open end of the elbow, of an axial sleeve fixed in the outer wall of the distributor and extending through the communicating 90 openings of the distributor and elbow so that its end engages the inner surface of the outer wall of the elbow, a pin fixed in the outer wall of the elbow and extending through said sleeve, and a rigid stop fixed on said pin beyond the distributor.

6. In a washing machine, the combination 95 of a conduit member having an outlet opening and a rotary distributing member having an axial intake opening communicating with said outlet opening, a pin fixed in one of said members and extending through their communicating openings, a sleeve fixed in the other of said members extending through their communicating openings and rotatably mounted on the pin, and rigid thrust bearings preventing substantial relative longitudinal movement of the pin and sleeve and positioned to maintain a narrow clearance space between the edges of the communicating 100 openings of the members.

In testimony whereof I have hereunto set my hand.

HENRY R. MERSELES.
